UNITED STATES PATENT OFFICE.

DE WITT C. SCOGAL, OF SEATTLE, WASHINGTON.

AUXILIARY VISE AUTOMATIC.

Application filed May 23, 1927. Serial No. 193,393.

The invention is an attachment for linotype, intertype or line casting machines which works in conjunction with the normal operation of the machine and automatically 5 operates to stop the machine when using the high mold for 18 to 36 point and also the mold for 42 point and upward.

This invention is an improvement over the device disclosed in an application for 10 the same thing which was filed April 7, 1927, with the Serial Number 181,694; in that the dog is made with three slideable members which will permit the device to operate while using the mold for 42 point 15 and upward in addition to operating with the high mold for 18 to 36 point.

The object of the invention is to provide an automatic safety stop which will not interfere with the normal operation of the 20 machine and which will automatically stop the machine when the first elevator travels beyond the correct position.

Another object of the invention is to provide means for constructing the vise automatic stop mold disc dog which will permit 25 a part of the dog to slide to automatically operate a safety device when the machine is operating normally while the remaining part remains stationary.

A further object of the invention is to 30 provide a slideable attachment on the vise automatic stop rod which will engage the upper portion of the dog.

A still further object of the invention is 35 to provide a slideable attachment on the vise automatic stop rod which will not interfere with the normal operation of the machine.

And a still further object of the invention 40 is to provide an attachment for automatically stopping the machine when the first elevator slide fails to stop at the correct position, which is of a simple and economical construction.

With these ends in view the invention 45 embodies a split dog which will replace the vise automatic stop mold disc dog, a bar slidably held on the vise automatic stop rod, a pin extending upward from the said bar and adaptable to engage the under side of 50 the head of the elevator slide, a spring for resiliently holding the bar upward, and clips that may be attached to the mold disc adjacent the mold opening.

Other features and advantages of the in-

vention will appear from the following description taken in connection with the drawings wherein:

Figure 1 is a sectional view through the first elevator and mold of a line casting machine with parts omitted showing the device 55 ready to use the mold for 42 point and upward with the first elevator slide in the upper position.

Figure 2 is a similar view showing an 60 arrangement for the 18 to 36 point mold with the slide in the lower position before the disc has moved toward the elevator and when the operator has failed to use the first 65 elevator slide filling piece.

Figure 3 is a detail showing a longitudinal 70 section through the vise automatic stop mold disc dog.

Figure 4 is a cross section on line 4—4 of Figure 3.

Figure 5 is an end view of the device shown 75 in Figure 3 showing an alternate arrangement.

Figure 6 is a view similar to that shown in Figure 2 with the mold disc moved to the 80 position of molding the type.

Figure 7 is a view showing the position 85 of the members in the normal operation of the machine for the regular mold showing that the lower portion of the dog may function without interference.

Figure 8 is a side view of the first elevator 90 with parts omitted which shows the position of the first elevator slide filling pieces.

In the drawings the device is shown as it 95 would be made wherein numeral 1 indicates the vise automatic stop mold disc dog, numeral 2 the bar which is slidably held on the vise automatic stop rod, and numeral 3 is a removable clip that is only used when the upper molds are being used.

The disc dog 1 is made as shown in Figures 3 and 4 with a lower section 4, an intermediate section 5 and an upper section 6. The lower section 4 is made with a circular opening 7 extending to the point 8 and a projection 9 that extends upward through a slot 10 in the member 5 and at the upper end of the projection 9 is a smaller projection 11 which extends into a slot 12 in the member 6. A spring 13 is provided in the device and it will be observed that the spring will resiliently hold the member 5 in the position shown, however it will permit 100 105 110

the lower portion 4 to slide as shown in Figures 6 and 7 when the members 5 and 6 are held and will also permit the members 4 and 5 to slide when the member 6 is held. It is also understood that this dog may be made square as shown in Figure 5 or may be made of any suitable shape as may be desired. This dog is slidably mounted in the circular opening provided in the frame for the vise 10 automatic stop mold disc dog.

The bar 2 is vertically and slidably held by a U-shaped band 14 which is placed around the vise automatic stop rod which is indicated by the numeral 15 and at the upper end of the bar 2 is a lever 16 which is pivotally attached to it by a pin 17 and which extends upward through the elevator frame which is indicated by the numeral 18 to a point 19 so that it will engage the under side of the first elevator slide head as it moves downward. The lever 16 is provided with a spring 20 which is attached to an eye 21 on the under side of the frame 18 to resiliently hold the lever and bar 2 in the upper position shown in Figure 1. It will be understood that any other suitable means may be used for slidably mounting the bar 2, for moving it downward when the elevator slide moves beyond the correct position, and for resiliently holding it upward.

The clip 3 may be readily attached to the disc adjacent the mold when using the upper mold and it will be observed that it will engage the upper portion of the dog 1 and thereby force the dog against the lower end of the bar 2 when the operator has neglected to throw the filling piece into place as indicated by the numeral 22, and the head of the elevator slide has moved downward beyond the correct position. It will be noted in Figure 8 that the filling piece 22 is pivotally mounted on the first elevator frame at the point 23 and when the upper mold is being used it is thrown over from the position shown in full lines to the position shown in dotted lines so that it will engage the under side of the upper end of the first elevator slide.

The machine is also provided with an additional filling piece which is indicated by the numeral 24 and when using the machine for the 42 point and upward molds both of the filling pieces may be placed under the head of the elevator slide which will permit the device to operate, however if either of these pieces are neglected the bar 2 will move downward and engage the end of the dog 1 and stop the machine as hereinafter described.

It will be noted that in the normal operation of the machine a screw as indicated by the numeral 25 and located in the upper end of the elevator slide engages a pin 26 at the upper end of the vise automatic stop rod 65 and forces this rod downward so that a

projection 27 will pass below the under side of the dog 1 and permit the dog to move outward to the position shown in Figure 3, however when the first elevator slide fails to move downward to the proper position 70 the pin 26 is not moved downward so that the dog 1 will engage the projection 27 and prevent the mold disc moving over so that the machine will stop. This new device operates to stop the machine when the elevator 75 slide moves downward too far when the upper or 18 to 36 point mold is being used as when the slide moves downward to such a position that it moves the bar 2 downward with the clip 3 in place the clip 3 will force 80 the dog 1 against the bar 2 and stop the machine.

It will be noted that the clip 3 may be made with a large surface as indicated by the numeral 28 as shown in Figure 1 or with a very narrow surface as shown in Figure 2 and when it is desired to use the machine for the 18 to 36 point mold the clips shown in Figure 2 will be used whereas when it is used for the mold for 42 point and upward 90 the clip shown in Figure 1 is used. These clips are placed directly opposite the molds with which they are being used so that they will engage the dog which is directly below the mold that is being used. This dog having three slidable members therefore permits the machine to be used for the regular mold, for the 18 to 36 point mold and for the mold for 42 point and upward and provides a positive stopping means for either of these 100 molds when not operating properly. It will be observed that the clips 3 are omitted for the regular mold and when using the device with the regular mold the upper portion of the dog will remain stationary as 105 shown in Figure 7; and when using it with the 18 to 36 point mold as shown in Figures 2 and 6 the upper slidable member only will remain stationary, however if the operator fails to use the filling 110 piece the bar 2 will move downward to the position shown in Figure 2 and thereby engage the end of the member 5 as well as 6 and stop the machine. When using the machine for the mold for the 42 point and 115 upward it is necessary to use both filling pieces and the clip with a large surface 28 is used so that it will engage both of the upper members of the dog and should the operator fail to use either of the filling 120 pieces or both the bar 2 will move downward until it engages the slidable member of the dog and thereby stop the machine.

It will be understood that changes may be made in the construction without departing from the spirit of the invention, one of which changes may be in the design or arrangement of the dog 1, another may be in the use of other means for supporting the bar 2 or in the use of a bar of another design, 130

and still another may be in the use of another means to engage the upper half of the dog 1 instead of the clip 3.

The construction will be readily understood from the foregoing description. To use the device the dog 1 and the bar 2 may be readily attached to or built into the machine and may remain in place while the machine is being used to operate with either of the molds. When using the upper molds the clip 3 may be attached to the disc and it will be observed that it will function to stop the machine when the first elevator slide moves beyond the correct position.

Having thus fully described the invention what I claim as new and desire to secure by Letters Patent is:

1. In a device of the class described, a split dog, means for resiliently holding the members endwise, said dog being adaptable to replace the vise automatic stop mold disc dog of a casting machine, a clip adaptable to be attached to the mold disc to engage a portion of the said dog, a bar slidable on the vise automatic stop rod, means whereby the said bar will be automatically moved downward to engage another portion of the said dog when the first elevator slide fails to stop at the correct position means for resiliently holding the said bar upward and another portion of the said dog adaptable to be engaged by the mold on the said mold disc so that it will engage the vise automatic stop rod to stop the machine and thereby perform the normal function of the dog.

2. In a device of the class described, a split dog, means for resiliently holding the sections, one of the said sections being adaptable to be engaged by the mold on the mold disc, removable means for engaging the other of the said sections, a bar slidably mounted on the stop rod and adaptable to be engaged by the sections of the said dog, and suitable means for operating the said bar as desired.

3. In a device of the class described, a split pin adaptable to replace the vise automatic stop mold disc dog of a casting ma-

chine, one section of the said pin being adaptable to be engaged by the mold on the said mold disc, clips on the said mold disc for engaging the other of the said sections and means for engaging the opposite end of the said pin to stop the operation of the machine as desired.

4. In a device of the class described, a resiliently held split pin adaptable to replace the stop dog of a line casting machine, said pin adaptable to permit the machine to operate normally, and means adaptable to engage the said pin to stop the operation of the said machine when the elevator slide fails to stop at a correct position, said engaging means being adaptable to operate for a plurality of positions of the said slide.

5. In an attachment for line casting machines, a slidable member having three slidable sections, means for resiliently holding the sections in relation to each other, said slidable member adaptable to replace the vise automatic stop mold disc dog of a casting machine, the lower of the said sections adaptable to perform the function of the vise automatic stop mold disc dog, the intermediate section adaptable to function to stop the machine when the operator fails to place the filling piece in position for using the 18 to 36 point mold, and the upper of the said sections adaptable to function to stop the machine when the operator fails to place the filling pieces in position for using the mold for 42 point and upward.

6. In a casting machine, a dog adaptable to replace the vise automatic stop mold disc dog having a plurality of slidable sections adaptable to function with the regular mold, and also additional molds to stop the machine automatically when the first elevator slide fails to stop at the correct position for the mold being used.

In testimony whereof I affix my signature.

DE WITT C. SCOUGAL.
